Patented Oct. 31, 1967

209,117

MEDICAL EXAMINATION TABLE OR THE LIKE

John Cuccio, Westport, Conn., assignor to Ritter Pfaudier Corporation, Rochester, N.Y., a corporation of New York

Filed Dec. 16, 1966, Ser. No. 5,064

Term of patent 14 years

(Cl. D83—1)

FIG.1

FIG.5

FIG. 1 is a top plan view of a medical examination table or the like showing my new design;

FIG. 2 is a side elevation thereof, the opposite side being a mirror image of the side shown;

FIG. 3 is a bottom plan view thereof;

FIG. 4 is an end elevation as seen from the left of FIG. 1; and

FIG. 5 is an end elevation as seen from the right of FIG. 1.

I claim:

The ornamental design for a medical examination table or the like, substantially as shown and described.
